UNITED STATES PATENT OFFICE.

FRED ORTHMANN, OF BROOKLYN, NEW YORK.

WINDOW SCAFFOLD.

Application filed March 14, 1922. Serial No. 543,698.

To all whom it may concern:

Be it known that I, FRED ORTHMANN, a citizen of the United States, and resident of the city of New York, borough of Brooklyn, in the county of Kings and State of New York, have invented a new and improved Window Scaffold, of which the following is a full, clear, and exact description.

My invention relates to a window scaffold 10 and aims to provide certain new and useful improvements in connection with a device of this character.

It is an object of this invention to provide a scaffold which may readily be applied 15 to and removed from a window without marring the woodwork of the same, and which will provide an absolute rigid support when in applied position.

It is a further object of this invention to 20 construct a device of the type described which may be associated with different portions of the frame with equal facility, and which when the same is not in use may be stored within a minimum amount of space.

25 Among further objects of this invention are that of providing a scaffold particularly adapted to be used adjacent frames of windows, and which may be placed in this position by an unskilled operator, and

30 Further objects of this invention will become apparent in the annexed specification taken in connection with the drawings which latter illustrates a practical embodiment of the same, and in which;

35 Figure 1 is a transverse sectional view of a window frame and sash associated therewith, and showing my improved scaffold applied to the lower part thereof.

Figure 2 is a similar view but showing the 40 scaffold applied to the upper portion of the window, and taken along the line 2—2 and in the direction of the arrow indicated in Figure 3.

Figure 3 is an inner face view of the device as illustrated in Figure 2.

Figure 4 is an enlarged fragmentary view of a detail of construction.

Figure 5 is a view taken along the line 5—5 of Figure 4, and

50 Figure 6 is an enlarged transverse view taken along the line 6—6 and in the direction of the arrows indicated in Figure 3.

In these views the reference numeral 10 indicates the window frame, mounting the 55 usual sash 11, and providing a ledge portion 12, it being noted that the essence of my

invention consists in the provision of a scaffold applicable to either the lower or upper portion of the frame in a manner hereinafter described, so that all parts of 60 the building adjacent to the window opening may be reached by an operator, supported by the said scaffold.

With a view of having the scaffold incorporate the maximum amount of strength 65 with a minimum amount of weight I preferably construct the same of angle irons, which in the embodiment illustrated are arranged to provide a cubical scaffold 13, it being noted in this connection that I preferably employ bolts 14 for securing the angle irons one to the other, and that a suitable floor portion 15 is provided upon which an operator may stand.

Secured adjacent the upper and inner end 75 of the cubical scaffold 13 are bars 16 which terminate in plate portions 17 as in Figure 3. Swingingly attached adjacent the outer lower edge of the said cubical scaffold are arms 18 in turn supporting ears 19 which 80 are swingingly attached adjacent their outer ends. This latter structure is provided with a view of insuring a maximum support to the scaffold in that socket members 20 are secured upon the inner face of the frame 10. 85 Also a pair of cables are provided, which cables have hooks 21 secured to their end portions, their bodies being attached to T head pins 22 in such a manner as to divide each cable into a relatively long portion 23 90 and a short portion 24. When the scaffold is to be applied to the lower portion of the frame, as in Figure 1 it will be seen that the sashes 11 are moved to their uppermost position, and the pin 22 is turned so that its 95 head may be inserted through the slot of the socket members 20, subsequent to which the pins are allowed to swing so that their heads extend transversely to the slot, it being ob-

vious that when the parts are in this position, any accidental detachment of the pins from the respective socket members is precluded. When the parts are thus disposed, it will be obvious that it will be necessary to utilize the longer portions 23 of the cables, 105 and the hooks secured to the ends of these portions are caused to engage in the openings of the ears 19 provided for this purpose, it being understood that the foot portions 17 of the bars 16 will bear against the 110 inner face of the frame and serve to additionally brace the scaffold.

Now with a view of additionally bracing the device it will be noted, reference being had to Figure 1, that a bracket has one of its ends secured adjacent the inner lower end of the cubical scaffold 13 and this bracket comprises two portions 25 and 26, each formed with a series of openings 27 through which bolts 28 may be extended. Thus it will be seen that the portion 25 comprises a longer 10 and a short shank, the former being coupled to the portion 26 when the ledge 20 is to be bridged as in Figure 1. Thus it will be understood that the cubical scaffold will be supported by means of the bracket thus provided so that any movement of the scaffold 15 will be prevented and the workmen will be free to utilize the same without any fear of a collapse of the parts.

However, assuming that the scaffold is to be supported in the position shown in Figures 2, 3 and 5 it will be seen that the portion 23 of the cable is detached from the arm 18 and the portion 24 thereof is substituted. Thus it is unnecessary to take up on the cable in view of the fact that the two portions thereof are of just such a length as to insure a proper tautness when the parts are in the position desired. Also, incident to the fact that the sashes 11, when the scaffold is to be moved to this position, and are slid downwardly, are of a width less than the width of the ledge 12, the longer leg of the portion 25 may be reversed as in Figures 2 and 5 to compensate for this difference in length although the bars 16 will remain at the same length. Further as in Figure 4 it will be noted that the bars 16 may

also be formed of two portions 29 and 30 formed with openings through which bolts may be extended so that in the event the scaffold encounters unusual difficulty, additions of framework, etc., the bars may be adjusted to compensate for this difference.

From the foregoing it will be understood that all of the objects of this invention are accomplished in that the scaffold is adapted for use in virtually any type of window or opening, and will provide a secure support upon which workmen may move without any fear that the scaffold is not adequately supported. It will also be appreciated that numerous modifications of structure might readily be resorted to without in the least departing from the scope of my claim; which is

A scaffold including a platform adapted to be positioned outside a window in one of two locations relative to the height of the window, and supporting means for the platform including a bracket, said bracket being adapted in one location of the scaffold to engage the bottom sill of the window and in another location of the scaffold to engage snugly the upper part of a sliding sash of the window, said bracket to that end including an L-shaped bracket member and means for attaching said bracket member to the scaffold to dispose either of the limbs of the L horizontally to adapt the bracket to engage either said sill or said sash at will, such attaching means being partially carried by both such limbs.

FRED ORTHMANN.
